Primary Examiner — Lauren D McVey(57) **CLAIM**

The ornamental design for a staple cartridge for surgical instrument, as shown and described.

DESCRIPTION

FIG. 1 is a side perspective view of a staple cartridge for surgical instrument, showing our new design without shading;

FIG. 2 is a top plan view thereof;

FIG. 3 is a bottom plan view thereof;

FIG. 4 is a side elevation view thereof;

FIG. 5 is another side elevation view thereof;

FIG. 6 is an enlarged front elevation view thereof;

FIG. 7 is an enlarged rear elevation view thereof;

FIG. 8 is a side perspective view of the staple cartridge for surgical instrument, showing our new design with shading;

FIG. 9 is a top plan view thereof;

FIG. 10 is a bottom plan view thereof;

FIG. 11 is a side elevation view thereof;

FIG. 12 is another side elevation view thereof;

FIG. 13 is an enlarged front elevation view thereof; and,

FIG. 14 is an enlarged rear elevation view thereof.

The wire frame lines shown throughout the views are intended to indicate surface contour.

1 Claim, 8 Drawing Sheets# US D893,717 S
